UNITED STATES PATENT OFFICE.

CHARLES F. MOSMAN, OF BRIDGEPORT, CONNECTICUT, ASSIGNOR TO THE
JENNINGS BROTHERS MANUFACTURING COMPANY, OF SAME PLACE.

DESIGN FOR A CLOCK-CASE.

SPECIFICATION forming part of Design No. 30,983, dated June 13, 1899.

Application filed May 17, 1899. Serial No. 717,215. Term of patent 7 years.

To all whom it may concern:

Be it known that I, CHARLES F. MOSMAN, a citizen of the United States, and a resident of Bridgeport, in the county of Fairfield and State of Connecticut, have invented and produced a new and original Design for Clock-Cases, of which the following is a specification, reference being had to the accompanying drawings, forming part thereof.

10 Figure 1 is a front elevation of my new design of clock-case, and Fig. 2 is a side view of the same.

As shown in the drawings, the leading and general feature of my design consists in an 15 ornamented pedestal, upon which is seated a Cupid, the latter supporting above its head the clock-case proper.

In detail my design consists in a triangular pedestal *a*, ornamented in French rococo and 20 shell effect. Upon the pedestal is gracefully seated a Cupid *b*, which supports by its hands

and legs a depending ornamental scroll-like stem *c* of the clock-case *d*. Said case is of substantially a cylindrical shape, and its front *e* is ornamented in French rococo style, while 25 the rear peripheral portion thereof is provided with scale and convex rib ornamentations *f* and *g*, respectively.

This case is applicable to other purposes than that herein named.

Having thus described my invention, what I claim, and desire to secure by Letters Patent, is—

The design for a clock-case, herein shown and described.

Signed at Bridgeport, Fairfield county, Connecticut, this 13th day of May, 1899.

CHARLES F. MOSMAN.
